DESIGN FOR A BUCKLE

Solomon Putman, Newark, N. J.

Application April 20, 1936, Serial No. 62,221

Term of patent 3½ years

To all whom it may concern:

Be it known that I, Solomon Putman, a citizen of the United States of America, residing in Newark, county of Essex, and State of New Jersey, have invented a new, original, and ornamental Design for a Buckle, of which the following is a specification, reference being had to the accompanying drawing, forming part thereof, wherein,

I claim:

The ornamental design for a buckle, substantially as shown.

SOLOMON PUTMAN.
